UNITED STATES PATENT OFFICE.

WILLIAM H. ZIEGLER, OF PITTSBURG, PENNSYLVANIA.

DESIGN FOR A RAIL-SPLICER.

SPECIFICATION forming part of Design No. 26,844, dated March 30, 1897.

Application filed January 22, 1897. Serial No. 620,273. Term of patent 14 years.

To all whom it may concern:

Be it known that I, WILLIAM H. ZIEGLER, a citizen of the United States of America, residing at Pittsburg, in the county of Allegheny and State of Pennsylvania, have invented a certain new and original Design for a Rail-Splicer, of which the following is a specification, reference being had therein to the accompanying drawings.

This invention relates to a certain new and original design for a rail-splicer, and is fully set forth in the accompanying specification and drawings, in which drawings—

Figure 1 is a perspective view. Fig. 2 is a longitudinal sectional view.

The principal features of my design consist in the plates *a*, being rigidly connected together in the center by the square bar *b*, said plates being beveled inwardly on their edges, as shown at *c c*. 20

Having fully described my invention, what I claim is—

The design for a rail-splicer as herein shown and described.

In testimony whereof I affix my signature 25 in presence of two witnesses.

WILLIAM H. ZIEGLER.
